UNITED STATES PATENT OFFICE.

LESLIE J. GOULD AND ROBERT GOULD, OF TORONTO, ONTARIO, CANADA.

METHOD FOR COMPENSATING FOR UNEVENNESS IN PRINTER'S TYPE.

Application filed May 28, 1926. Serial No. 112,390.

The invention relates to improvements in methods for compensating for unevenness in printer's type as described in the present specification and shown in the accompanying drawings which form part of the same.

The invention has for its object to produce a new and simple method which will both facilitate and expedite the process of compensating for unevenness in printer's type, one which will demand very little skill on the part of the operator.

The invention consists mainly of the novel method of performing this work as described in the specification hereinafter following and described in the accompanying drawings, of which Figure 1 is a vertical sectional view of a "make-ready" according to the present invention, interposed between the packing and cylinder, surmounting which is an outline of type. In this view, the packing, the make-ready, and the uneven surface of the type are for purposes of illustration greatly exaggerated.

Figure 2 is a perspective view of a "make-ready" constructed according to the present invention.

Like numerals of reference indicate corresponding parts in each figure throughout the drawings.

It is customary after a printer's form is compiled to compensate for any unevenness of type by constructing what is known or generally termed a "make-ready". This is accomplished by taking a pull off the form, after which this pull is inspected to ascertain unevenness which will be clearly evident from the faintness and heaviness of portions of the printing. The weak spots are then bolstered up by pasting one or more pieces of tissue on the back of the pull, the amount of packing for each particular weak spot being more or less a matter of judgment and experience.

This pull is then placed upon the cylinder or platen and a corresponding thickness of packing removed from the cylinder in order to compensate for this padded make-ready.

The operation of making-ready will have to be repeated by taking further pulls and similarly patching this until an absolute evenness of type has been arrived at.

In the present invention, the process consists of taking a pull off the form and cutting out the heavy impressions, which are

naturally indicative of upstanding or high-type. This pull is placed in register upon the cylinder and a number of sheets of tissue, waxed upon the underside, placed thereover. Superimposed over these sheets is an unwaxed tissue in order that when a pull is taken upon this mass this covering tissue may bear the printing and the underlying waxed tissues take the impression, which impression will disturb or break the wax upon the underside of the tissues causing the typing to "show-up white". For the purpose of more clearly examining this waxed typing, a card—preferably of dark colour—is placed under the tissue sheet. Each sheet is thus examined and, wherever this waxed typing appears, the same is cut out of the sheet; from which it will be evident that the stronger the impression (caused, of course, by the higher type) the larger the number of sheets from which such impression will be removed, and vice-versa with fainter impressions.

The waxed sheets together with the original pull are then placed beneath the packing on the cylinder, after first having removed a quantity of packing equal to the thickness of this tissue padding.

From the foregoing it will be evident that this newly devised process of make-ready will most efficiently, and without requiring skill, judgment or long experience, compensate for any unevenness which exists in the type of the form.

In Figure 1 of the drawings, the reference numeral 1 designates a "make-ready" constructed according to the preceding process showing the cut-out portions 2. 3 is the packing and 4 designates the surface of the type.

Figure 2 shows a typical pad of waxed tissues in which 5 are cut-out portions of different depths for compensating for type variations.

What we claim is:—

1. The method of compensating for unevenness in printer's type which consists in placing a number of sheets of waxed tissue upon the cylinder or platen of a press, taking an impression of the set-up type thereupon, cutting out of the waxed tissues certain impressions, and placing these tissues as a pad beneath the packing to serve as a make-ready.

2. The method of compensating for un-

evenness in printer's type which consists in placing a number of sheets of waxed tissues together with a superimposed sheet of un-waxed material upon the cylinder or platen 5 of the press, taking a pull upon this mass so that the uppermost sheet receives the printing and the underlying tissue receives the impression; cutting out of the waxed tissues certain impressions, and placing these 10 tissues as a pad beneath the packing to serve as a make-ready.

3. The method of compensating for unevenness in printer's type which consists in taking a pull off the set-up form, cutting 15 out of the same the heavy impressions, plac-

ing the mutilated pull in register upon the cylinder or platen together with a number of superimposed sheets of tissue of which the uppermost sheet only is unwaxed; taking a further pull upon this mass so that the 20 uppermost sheet receives the printing and the underlying waxed tissue receives the impression; cutting out of the waxed tissues certain impressions, and placing the 25 pulls and these tissues as a pad beneath the packing to serve as a make-ready.

Signed at Toronto, Ontario, Canada, this 21st day of May 1926.
